UNITED STATES PATENT OFFICE.

EUGENE CHRISTOPHER, OF URBANA, ILLINOIS.

SAFETY BASE FOR PORTABLE GRANDSTANDS.

Application filed October 25, 1926. Serial No. 143,872.

This invention relates to improvements in a safety base for portable grandstands, and has for one of its principal objects the provision of a portable grandstand, sometimes known as "knockdown bleachers," which includes a novel and positively operating safety device to prevent collapse.

One of the important objects of this invention is to provide, in a portable grandstand 10 or the like, a plurality of members for ready assembling to conveniently and comfortably seat a number of people for viewing games or the like, which grandstands can be taken down when not in use, and which, when in 15 use, will not be subject to sidewise or other displacement or collapse even under a considerable weight or even in the event of an insecure, uneven, or soggy ground support.

Another important object of this invention 20 is the provision of a quickly assembled and disassembled base construction for a portable grandstand or the like, which will constitute an integral portion of the grandstand itself, and be so affixed thereto as to be readily 25 disengaged of and packed in a small compass when the grandstand is taken apart.

Another and still further important object 30 of this invention is the use of a novel base construction in connection with a portable grandstand, which shall act to distribute any weight placed thereon or any excess strain or stress upon one or more of the members so that in the event any supporting element becomes weakened or is placed upon an insecure 35 or uneven foundation such as spongy ground or the like, a collapse will be prevented.

Other and further important objects of the 40 invention will be apparent from the disclosures in the accompanying drawings and following specification.

The invention, in a preferred form, is illustrated in the drawings and hereinafter more fully described.

In the drawings:

Figure 1 is a perspective view of a portion 45 of a portable grandstand constructed in accordance with the principles of this invention.

Figure 2 is a detail top plan view of a portion 50 of the supporting base.

Figure 3 is a side elevation viewed from the rear of the construction shown in Figure 2.

Figure 4 is a top plan detail view of another part of the supporting base.

Figure 5 is a side elevation of the apparatus 55 shown in Figure 4.

As shown in the drawings:

The reference numerals 10 indicate generally a plurality of supporting boards or sleepers adapted to be laid upon the ground in the place where the portable grandstand is to be erected. Mounted in turn upon each supporting sleeper 10 is a stringer 12 supported in any suitable manner at one end of the sleeper and extending upwardly and rearwardly at 60 an angle of some twenty-five to forty degrees, as best shown in Figure 1.

Supports for the stringers 12 in the form of jacks or the like 14 are provided, each composed of two members positioned at an angle 65 and connected at the top, and having a notch in the top for the reception of the stringer 12. Locking means 18 in the form of blocks or similar elements are nailed or otherwise secured to the stringers 12 and are adapted to 70 receive the upper ends of the jacks 14 and support the same in desired relation to the stringers 12.

It is obvious that any number of supporting sleepers 10 and stringers 12 may be used in a 75 grandstand unit together with a corresponding number of jacks, and extending longitudinally across the stringers 12 and at right angles thereto is a plurality of planks 20 which constitute seatboards, these seatboards being 80 supported by extensions in the form of metal straps 22. A number of footboards 24, corresponding to the number of seatboards, but one less in number, are provided, these footboards 24 being likewise supported by metal 85 straps or brackets 26 extending downwardly 90 from the stringers 12 and attached to the under faces thereof by means of lag screws or in any other suitable manner. The planks constituting the seats and footboards are 95 readily removable from the stanchions 22 and brackets 26, thereby providing for an easy and ready dismantling of the entire structure.

If portable grandstands such as described 100 above are placed upon filled or soft ground, or on a slope, all of the weight will be thrown upon the legs on one side of the jacks 14 so that these legs will sink into the ground, causing the bleachers to crash or collapse side- 105 wise. In order to guard against such a contingency and accident a plurality of jack locks 28 are provided, adapted to be placed behind the legs of the jacks 14 these jack locks being in the form of longitudinally ex- 110 tending members supported in proper position on the sleepers 10 by means of jack lock

irons 30 attached to the sleepers 10 and having their free ends bent upwardly and forwardly in the form of hooks 32. In order to provide for a positive joint between the jack lock members in a long string of bleachers an angular cut is provided at the end as shown at 34 in Figures 2 and 4, this cut being at an angle of approximately thirty degrees in each case, so that the ends of the jack lock members may be closely fitted together under the hooks 32.

Securely attached to the under faces of the jack locking members 28 at the point where the ends of the legs of the jacks 14 would ordinarily contact with the ground is a plurality of blocks or flat supports 36, these being attached to the jack locks 28 by means of screws or bolts 38, and in each case extending forwardly therefrom to receive and support the foot or leg of the jack 14. This construction is shown in perspective in Figure 1, and in detail in the remaining figures. The ends of the legs of the jacks are beveled to provide for a full bearing surface on the base member or block 36.

In Figures 2 and 3 are shown the construction at the rear of the stand where the legs 14 of the jacks practically contact with each other at their lower ends, the blocks 36 being accordingly positioned adjacent each other and adapted to be placed directly on the ground.

In Figures 4 and 5, the ends of the legs of the jacks being shorter, do not quite come together at their ends, and accordingly the blocks 36 are spaced apart along the length of the jack lock 28.

As best shown in Figure 3, cleats 40 are provided on the under faces of the jack lock members 28 adjacent the point where the sleeper 10 passes thereunder, so as to assure a proper positioning of the sleeper 10 with respect to the jack locks and also with respect to the remaining members.

It will be seen that this form of structure can be readily built up to accommodate a large number of persons, and by means of the improved base construction provided there is no possibility of any undue strain being

placed upon any particular part, and therefore any resultant breakage or collapse of the structure due to its being positioned upon soft, spongy, or uneven ground will be prevented, as the entire structure is so locked together and so adequately supported by means of the augmented area as applied to the ground, that a very safe foundation for a weight greatly in excess of the capacity of such a stand is provided.

I am aware that many changes may be made and numerous details of construction varied throughout a wide range without departing from the principles of this invention, and I therefore do not purpose limiting the patent granted hereon otherwise than as necessitated by the prior art.

I claim as my invention:

In a portable grandstand, a series of sleepers adapted to be placed on the ground, a corresponding number of stringers mounted on said sleepers at an angle thereto and supported at one end thereof, a plurality of jacks for supporting the stringers, said jacks being readily removable therefrom, a plurality of upstanding extending stanchions spaced along each stringer, and seatboards on the stanchions, a plurality of downwardly extending brackets on each stringer positioned alternately with the stanchions and footboards in the brackets, and a plurality of members extending across the sleepers behind the legs of the jacks to maintain the jacks in desired position, together with supports for the legs of the jacks on said members, said cross members comprising bars removably mounted on the sleepers, and a pair of foot supports for each jack, each of said foot supports comprising a rectangular base board fastened to the under side of said locking bars and in the same plane as the sleepers, thereby adapted to be placed on the ground, certain of said base boards adapted to abut the sleepers and certain other of said base boards adapted to abut each other to prevent horizontal sliding movement.

In testimony whereof I affix my signature.

EUGENE CHRISTOPHER.
